ATTORNEY

UNITED STATES PATENT OFFICE

WILLIAM B. FAHNESTOCK, OF WYOMING, OHIO

FOLDING DESK

Application filed April 6, 1928. Serial No. 267,873.

This invention relates to a folding desk.

An object of the invention is the production of a desk of the indicated character, which will be of simple and practical construction, and light in weight, yet sturdy in use.

Another object of the invention is the production of a desk which may be readily folded to occupy but little space when not in use, and which may also be readily opened for use, and which when in use will stand firmly without tilting or rocking.

Another object of the invention is the provision in a folding desk of a receptacle or repository for sundry articles, such as stationery and graphic instruments, which receptacle or repository, will assume an upright position when the desk is opened for use, and when folded, the articles being kept from falling out of the repository, and being held conveniently accessible when the desk is in use.

The nature of the invention and its distinguishing features and advantages will appear when the following specification is read in connection with the accompanying drawing, in which—

Figure 1 is a perspective view of a desk constructed in accordance with the invention, the desk being opened for use.

Figure 2 is a sectional view of the desk in folded condition.

Generally stated the desk of the present invention comprises a top 10, a supporting structure or arrangement 11 connected with and adapted to support the top 10 in a substantially horizontal position for use, and which is also adapted to be folded or collapsed, and a receptacle or repository 12 suspended from or connected with the top 10 for sundry articles such as stationery and graphic instruments.

The top 10 may be made of any preferred material, and is of rectangular shape. The structure or arrangement 11 includes a cross block 13 hingedly connected as at 14 to the underside of the top 10, at or near the middle thereof, and having an abutment face 15 which contacts with the under side of the top so as to hold the block 13 at an angle with

respect to the top 10. The block 13 has rigidly connected therewith legs 16 in spaced relation, and are also connected together by a cross piece 17. A leg 18 is hingedly connected as at 19 with the cross block 13 substantially centrally of the lower edge. The upper end of the leg 18 has an abutment face 20 which contacts with one side of the block 13 in one position of the leg 18. The underside of the top 10 has secured thereto abutments or stops 21. Brace members 22 are respectively pivotally connected as at 23 with the legs 16, and are respectively engageable with the abutments or stops 21.

One end of the top 10, the far end thereof, has suspended therefrom the receptacle or repository 12 hereinbefore mentioned. The said receptacle or repository 12 is hingedly connected as at 24. The hinge connection is such that the repository will always assume an upright position when the desk is open or in set up condition for use, or when it is folded and not in use, as shown in Fig. 2. The repository 12 is open at the top, and it will be apparent that sundry articles placed therein will always be held conveniently accessible, and will not fall out of the repository, either when setting up the desk for use or when folding it.

When it is desired to open or set up the desk for use it is only necessary to grip the end of the top 10 remote from the receptacle or repository 12, with the legs 16 and 18 in contact with the floor, and then exerting an upward swinging movement to the top 10 the legs 16 and 18 will assume an angular relationship with the abutment face 15 of the block 13 in contact with the under face of the top 10, and the abutment face 20 of the leg 18 in contact with the block 13. The brace members 22 may then be swung respectively into engagement with the abutments or stops 21. At the same time the receptacle or repository 12 will assume an upright position as shown in Fig. 1. The top 10 of the desk will thus be held firmly in a slightly inclined position. In fact the desk in its entirety will firmly rest on the floor with the desired stability.

When it is desired to collapse or fold the

desk, the brace members 22 are first disengaged from the abutments or stops 21, whereupon the top 10 may be swung on the hinges 14, and at the same time the leg 18 will swing on its hinge, and the receptacle or repository 12 will also swing on its hinges to an upright position, as shown in Fig. 2. It will therefore be apparent that the desk thus collapsed or folded will occupy but comparatively small space when not in use.

If desired the far end of the top 10 on the upper surface thereof may be provided with a suitable holder 25 for accommodating pencils or pens. The holder 25 is designed to hold graphic instruments from rolling down the upper surface of the top 10, and will also hold the instruments therein even when the desk is in folded or collapsed condition.

I claim:

1. A foldable desk comprising a top, a foldable supporting structure connected with the top for supporting the top, and a receptacle movably suspended from one end of the top, said receptacle being open at the top, said receptacle being so suspended that it may move relatively to the top when the desk is being opened for use, or being folded, to assume an upright position.
2. In a foldable desk, a top, and a repository for sundry articles, said repository being open at the top, said repository being hingedly suspended from one end of the top so that it may move relatively to the top when the desk is being opened for use, or being folded, to assume an upright position.
3. A foldable desk comprising a top, a cross block hingedly connected with the top, said block being formed to contact with the underside of the top, legs rigidly connected with the block, a leg having an abutment, hingedly connected with the block, braces pivotally connected respectively with the rigidly connected legs, stops on the underside of the top, and said braces being respectively engageable with said stops, said abutment being engageable with said block, the construction and arrangement of the legs, stops, braces and block being adapted to support said top substantially horizontally disposed for use, and said legs, braces and block being relatively movable for the purpose of folding the desk.

Signed at Cincinnati, in the county of Hamilton and State of Ohio, this 3rd day of April, A. D. 1928.

WILLIAM B. FAHNESTOCK.
